[54] COMBINED CEILING FAN COVER PLATE
AND BLADE CONNECTORS

[56]

References Cited

U.S. PATENT DOCUMENTS

D. 47,079 3/1915 Kouyoumjian D23/165
D. 82,179 9/1930 Ringwald D23/158

Primary Examiner—James R. Largen
Attorney, Agent, or Firm—Robert J. Van Der Wall

[] Term: 14 Years

[57]

CLAIM

The ornamental design for a combined ceiling fan cover plate and blade connectors, as shown and described.

DESCRIPTION

FIG. 1 is a bottom plan view of a combined ceiling fan cover and blade connectors showing my new design; and

FIG. 2 is a side elevation view thereof.

The fragmentary broken line representation of fan blades in FIG. 1 and of a ceiling fan in FIG. 2 are for purposes of illustration only.

U.S. Patent

Aug. 26, 1980

Des. 256,614